DESIGN FOR A SAVINGS BANK

Esther Brann, New York, N. Y.

Application December 2, 1939, Serial No. 88,639

Term of patent 3½ years

To all whom it may concern:

Be it known that I, Esther Brann, a citizen of the United States, residing at 1420 Grand Concourse, in the Borough of Bronx, city and State of New York, have invented a new, original, and ornamental Design for Savings Bank, of which the following is a specification, reference being had to the accompanying drawing, forming part thereof.

In the drawing, Fig. 1 is a perspective view of the bank showing the front and one side; and Fig. 2 is a rear view of the same bank.

I claim:

The ornamental design for a savings bank, as shown.

ESTHER BRANN.
